UNITED STATES PATENT OFFICE.

GEORGE S. PARKER, OF PETERBORO, NEW HAMPSHIRE, ASSIGNOR TO PARKER BROTHERS, INC., OF SALEM, MASSACHUSETTS, A CORPORATION OF MAINE.

CARD OR CHART GAME.

Application filed April 28, 1927. Serial No. 187,189.

This invention relates to card or chart games, and particularly to games adapted to be played by a group of players seated about a table.

5 In order that the principle of the invention may be readily understood, I have illustrated and shall describe the articles or pieces which are preferably employed in playing the game, and shall also describe 10 the preferred manner of playing the game.

Referring to the drawing:

Fig. 1 is a plan view representing a series of cards or charts, the number depending upon the number of players;

15 Fig. 2 is a similar view of a few of the playing pieces, a relatively large number of which are employed and which may be all duplicates of each other; and

20 Fig. 3 shows a few of the calling pieces here represented as of disk like form and having upon a face thereof certain data to be referred to.

Any number of players may participate in 25 playing the game. Obviously the greater number of players the greater the interest in the game. Therefore, a relatively large number of charts or cards are provided, and in playing the game each player receives one of the charts or cards. Three such 30 charts or cards are indicated at 1, 2, 3, respectively in Fig. 1. In addition, a relatively large number of playing pieces are provided, as indicated at 4 in Fig. 2, and also a relatively large number of calling 35 pieces shown at 5 in Fig. 3. Each of the cards or charts has a number of spaces 6, here shown as squares, which are uniform in size and arrangement throughout the entire series of cards. The said spaces are 40 arranged in suitable rows, and preferably so as to provide a plurality of horizontal rows which, when arranged as shown, present vertical columns as well as diagonal sloping rows. In that form of the invention 45 shown, I have provided five horizontal rows of spaces upon each card, and as the spaces of the horizontal rows are arranged one under another, there are thus provided five columns or vertical rows. There are 50 also two inclined rows each having five spaces running diagonally from corner to corner. Each space or square is numbered, and desirably the numbers upon each card or chart are differentiated more or less from 55 those upon each of the other cards. The

numbers upon each card may be arbitrary or according to some special arrangement, and the invention is in no wise limited in this respect.

If desired, I may indicate upon the margin of each card the total of the numbers in each row, including the horizontal rows, the vertical rows, and the two diagonal rows of five figures. Such totals are provided mainly as a matter of convenience. 60 65

Along one edge of each card or chart and in relation to the rows, I provide symbols of some sort. In that form of the invention shown, the symbols are placed at the top of each card, so as to be at the top of each 70 vertical row. In that form of the invention shown, I have chosen letters for illustration, and in this instance the letters spell the word "Hokum". Obviously any other suitable word may be employed, or instead 75 the columns may be designated by such symbols as a moon, star, dagger, asterisk, eagle, or some other bird or animal. Desirably one or more of the spaces or the numbers therein upon each chart shall be 80 distinguished from the remainder or majority of such spaces by some special design or color, so as to indicate a special significance or greater value, such, for example, as the number "37" upon the card 1, the 85 number "45" upon the card 2 and the number "41" upon the card 3.

It will be observed that in the disclosed form of my invention the number of horizontal rows is the same as the number of 90 vertical rows, and there are also provided upon each card two oblique rows of the same number of spaces, and this is the preferred arrangement, though my invention is not limited thereto. I also provide a large 95 number of playing pieces shown at 4 in Fig. 2, which may be all colored the same and may consist of short cylinders of wood of a diameter sufficiently large to cover the number or numbers upon any of the squares 100 or spaces. There should be provided a sufficient number of these playing pieces to furnish each of the players, no matter how many players there may be, with a suitable number of pieces, say, twenty-five. In 105 addition, I also provide a number of calling pieces on which I place certain data. In the present instance, such data consists of a letter, which is one of the letters in the word "Hokum", it being understood that if 110

2 symbols other than letters are employed, "Master" thoroughly mixes the calling pieces and conceals the numbers thereon, and begins again to draw the calling pieces and call off the data, as before. The game continues for a certain number of hands, such as ten, or 70 for a predetermined period of time, or until some single score (as, for example, 1000) is obtained by some player.

5 upon some card in the vertical row at the top of which appears the letter or other symbol upon this calling piece. For example, referring to the card or chart 1, one of the calling pieces might have thereon 10 the letter "O" and the number "24", or the letter "K" and the number "37", etc. There should be provided calling pieces corresponding to the numbers on all the cards together with the letter or symbol at 15 the top of the vertical row or column where-in such number appears.

In playing the game, the players are grouped about a table, and each one is provided by lot or otherwise with one of the 20 cards or charts. He is also furnished with, say, twenty-five playing pieces. The calling pieces are all in charge of one of the players, who may be called the "Master", and he may arrange the calling pieces face down, so that 25 the data thereon may not be known until it is called, or such calling pieces may be drawn from a bag or vessel one at a time.

The object of the game is to complete a row, whether horizontal, vertical or oblique, 30 before any other player. If a row is first completed which includes some space that has a number of special significance or value (such, for example, as the space "37" on card 1, space "45" on card 2, or space "41" 35 on card 3), the score or sum of the numbers in that row may be doubled or increased according to some established rule.

In playing the game, as the "Master" calls the letter or other symbol and the number 40 appearing upon each calling piece drawn, the players repeat the data, and any player or players, finding on his chart the number in the column headed by the symbol, covers that number with one of the playing 45 pieces. The "Master" may, of course, also be provided with a card or chart and playing pieces. When a group is playing, one or more of the players will find the called number with symbol upon their cards, but others 50 will not.

The player to win the hand is the one who first places a fifth piece so as to complete any row upon his or her card. Such player immediately calls "Game" or "Hokum", or 55 any agreed upon word to signify he has won the hand, and the other players thereupon cease to play. The numbers in the completed row of that hand are then added, and such total is given as his or her score. In 60 case the winning row on the card or chart runs through some specially designated space, a premium is added to the score, preferably by doubling the same. A new hand is then started, all the playing pieces having previously been removed from the charts. The 65

I am well acquainted with the game known as "Lotto", from which the present game 75 differs in many important respects, some of which I will refer to. In accordance with the present invention, all of the spaces are numbered, whereas in the game of "Lotto", there are numerous vacant spaces. Moreover each vertical row or column is designated by some letter or other symbol, and one or more of the spaces on each card are colored or otherwise distinguished from the majority of the spaces, as already described. 80 Moreover, the object of the game is wholly different in that in my invention the object is to complete a row and not to cover all the spaces having numbers. Moreover, the counting or scoring in the present game is wholly 85 different from that of "Lotto".

I have in Fig. 1 of the drawing represented upon one vertical edge, as well as at the ends of the two diagonal rows of five figures, 90 the sums of the figures in the various rows.

I have in the specification referred to the use of calling pieces. Such term is one of broad significance, and includes cards or the like. Instead of employing disks, as shown in the drawings, I may employ a pack or set of cards which would bear the same data as already referred to upon the disks. Such set of cards may be shuffled and held by the "Master", or may be placed face down as a set upon the table and drawn one at a time by the "Master".

Having thus described the articles or pieces entering into the playing of the game and the best mode known to me for playing the game, I desire it to be understood that although specific terms are employed, they are used in a generic and descriptive sense, and not for purposes of limitation, the scope of the invention being set forth in the following claims.

Claims:

1. A game comprising a plurality of cards or charts, each having a plurality of rows of spaces, each space having a number, said cards or charts bearing along appropriate edges the sums of the numbers in said rows, each of said cards or charts also having a series of symbols extending across a side thereof to designate the rows, a plurality of playing pieces adapted to be placed upon called numbers upon said cards or charts, and a plurality of calling devices, each bearing a number and a symbol pertaining to a row on said cards or charts.

2. In a game, a plurality of cards or charts

each having a plurality of rows of spaces, each space having a number, said cards or charts bearing along appropriate edges the sums of the numbers in said rows, each of 5 said cards or charts also having a series of symbols extending thereacross at the upper ends of the rows to designate the rows, a plurality of playing pieces adapted to be placed upon called numbers upon said cards or 10 charts, and a plurality of calling devices, each bearing a number and a symbol pertaining to a row on said cards or charts.

3. A game comprising a plurality of cards or charts, each having a plurality of rows 15 of spaces, each space bearing a number, whereby every space of each card or chart is numbered, each of said cards or charts having a series of symbols across a side thereof to designate the rows, at least one 20 of said numbered spaces being distinguished from the other spaces otherwise than by merely the number thereof, thereby giving the space a special significance, said cards or charts bearing along appropriate edges the 25 sums of the numbers in said rows, a plurality of playing pieces adapted to be placed upon called numbers upon said cards or charts, and a plurality of calling pieces each bearing a number and a symbol pertaining to a 30 row on said cards or charts.

4. A game comprising a plurality of cards or charts, each having a plurality of rows of spaces, each space bearing a number whereby every space of each card or chart 35 is numbered, each of said cards or charts having a series of symbols extending across a side thereof to designate the rows, at least one of said numbered spaces being distinguished from the other spaces by color, there- 40 by giving said space a special significance, said cards or charts bearing along appropriate edges the sums of the numbers in said 45 rows, a plurality of playing pieces adapted to be placed upon called numbers upon said cards or charts, and a plurality of calling pieces each bearing a number and a symbol pertaining to a row on said cards or charts.

5. A game comprising a plurality of cards or charts each having a plurality of rows 50 of spaces, each space bearing a number whereby every space of each card or chart is numbered, each of said cards or charts having a series of symbols extending across a side thereof to designate the rows, the 55 central space of said numbered spaces being distinguished from the other spaces otherwise than merely by the number thereof, thereby giving said space a special significance, said cards or charts bearing along appropriate 60 edges the sums of the numbers in said rows,

a plurality of playing pieces adapted to be placed upon called numbers upon said cards or charts, and a plurality of calling pieces each bearing a number and a symbol pertaining to a row on said cards or charts. 65

6. A game comprising a plurality of cards or charts, each having a plurality of series of spaces, said spaces bearing respective numbers, each of said cards or charts having a series of symbols across a side thereof to 70 designate the rows, at least one of said spaces being distinguished from the other spaces otherwise than by merely the number thereof, thereby giving the space a special significance, said cards or charts bearing along appropriate edges the sums of the numbers in the rows, a plurality of playing pieces adapted to be placed upon called numbers upon said cards or charts, and a plurality of calling pieces each bearing a number and a symbol pertaining to a row on said cards or 75 charts.

7. A game comprising a plurality of cards or charts, each having a plurality of series of spaces, each space bearing a number, each of said cards or charts having a series of symbols extending across the tops of the rows thereof to designate the rows, at least one of said numbered spaces being distinguished from the other spaces otherwise than by 80 merely the number thereof, thereby giving the space a special significance, such cards or charts bearing along appropriate edges the sums of the numbers in the rows, a plurality of playing pieces adapted to be placed upon called numbers upon said cards or charts, and a plurality of calling pieces each bearing a number and a symbol pertaining to a row of said cards or 85 charts. 90

8. A game comprising a plurality of cards or charts, each having a plurality of rows of spaces, each space bearing a number, each of said cards or charts having a letter at the edge of each row to designate the rows, said letters spelling a word, at least one of said numbered spaces being distinguished from the other spaces otherwise than by merely the number thereof, thereby giving the space a special significance, such cards or charts bearing along appropriate edges the sums of the numbers in the rows, a plurality of playing pieces adapted to be placed upon called numbers upon said cards or charts, and a plurality of calling pieces each bearing a number and a symbol pertaining to a row of 95 said cards or charts. 100

In testimony whereof, I have signed my name to this specification.

GEORGE S. PARKER.
